UNITED STATES PATENT OFFICE

ROBERT B. LONG, OF DAYTON, OHIO, ASSIGNOR TO OHMER FARE REGISTER COMPANY, OF DAYTON, OHIO, A CORPORATION OF NEW YORK

COUNTER AND RESETTING MECHANISM THEREFOR

Application filed September 2, 1926. Serial No. 133,241.

This invention relates to an improved counter and a resetting means therefor.

More specifically, the invention relates to a counter actuated by an arm which may be either rotated or oscillated, and if oscillated may be moved either forward or backward to advance the figure wheels of the counters.

Another object of the invention is to provide means whereby the counters will not be overthrown regardless of how fast or how slow the actuating means therefor may be operated.

Another object of the invention is to provide a novel transfer pinion disengaging means so that the transfer pinions may be disconnected from the Geneva wheels on the resetting operation and may be locked in engagement therewith when the figure wheels are being actuated.

Another object of the invention is to provide means whereby the movement of the resetting means is arrested when the figure wheels have been returned to zero position.

Another object of the invention is to provide a simple, compact and inexpensive arrangement of parts which will be positive in operation and of such simple construction that there will be but little possibility of the device getting out of order.

Other objects and advantages of the invention will appear in the detailed specification which follows. Referring more specifically to the drawings in which like characters are used throughout to designate similar parts;

Figure 1 is a front elevational view partly in cross section.

Figure 2 is a similar rear elevational view.

Figure 3 is a top plan view.

Figure 4 is a detailed fragmentary view of the left hand portion of the machine with the resetting knob pushed inwardly so as to disengage the transfer pinions from the Geneva wheels.

Figure 5 is an elevational view partly in cross section on the line 5—5 of Figure 1, looking in the direction of the arrows.

Figure 6 is an elevational view partly in cross section on the line 6—6 of Figure 3, looking in the direction of the arrows.

Figure 7 is an elevational view partly in

cross section on the line 7—7 of Figure 3, looking in the direction of the arrows.

Figure 8 is a view similar to Figure 7 and showing the transfer pinions disengaged from the Geneva wheels.

Figure 9 is an elevational view partly in cross section on the line 9—9 of Figure 1, looking in the direction of the arrows, and

Figure 10 is a view similar to Figure 9 but showing the relative position of the parts after the resetting knob has been partially rotated.

Referring more specifically to the drawings, the U-shaped casing 1 is provided with end walls 2 and 3. A shaft 4 is mounted in said walls 2 and 3 and is provided with a collar 5 on the outside of the wall 3 and a collar 6 near the end of the shaft projecting through the wall 2, the object of the collars 5 and 6 being to prevent longitudinal movement of the shaft. The shaft 4 is provided with a channel 7 extending approximately for the distance between the end walls 2 and 3.

Figure wheels 8 are rotatably mounted on the shaft 4, each of which figure wheels is provided with a dog 50 adapted to engage the abrupt wall of the channel 7. Each of the figure wheels is provided with a twenty-toothed gear 9 on one side and a disk 10 on the other side provided with a cutaway portion forming two gear teeth, not shown.

This mechanism constitutes the well known Geneva wheels which cooperate with the transfer pinions 11 mounted on a shaft 12 carried by the arms 13 of the U-shaped member 14 which is pivoted on the shaft 15.

The member 14 has a downwardly and rearwardly depending flange 16 which extends beyond the end wall 3 and is provided with an inwardly extending ear 17 which engages a disk 18 on the hollow shaft 19, on which is mounted the knurled knob 20. The disk 18 is provided with a cam-portion 21, said cam portion 21 being merely a cutaway part of the disk 18, as is clearly shown in Figure 2.

A spring 22 is secured to the flange 16 at one end, is coiled around the shaft 15 and is secured at its other end in a bracket 23 secured to the end wall 3 of the casing. The

function of the spring 22 is to pull the member 16 towards the shaft 4 when the knob 20 is moved inwardly so as to bring the cam portion 21 beneath the ear 17.

The hollow shaft 19 is provided with a shoulder 24, and a coiled spring 25 is interposed between the shoulder 24 and the collar 5, said spring being between the inner periphery of the hollow shaft 19 and the outer periphery of the shaft 4. The spring 25 therefore tends to normally push the knob 20 away from the collar 5 or into the position shown in Figure 1.

An oscillatable bracket 26 is provided with arms 27 and 28 rotatably mounted on the shaft 15. The arm 28 of the bracket is best shown in the Figures 9 and 10, in which figures it will be noted that the rearwardly extending portion of the arm 28 is engaged by a cam 29 carried by the hollow shaft 19. The forwardly extending portion of the arm 28 is hook-shaped to receive a pin 30 carried by the disk 18. A spring 31 is coiled about the shaft 15 and has its opposite ends secured to the arm 28 and bracket 23. The function of the spring 31 is to tend to pull the rearwardly extending portion of the arm 28 toward the shaft 4, but this movement is resisted by the cam 29 unless the knob 20 is pressed inwardly against the tension of the spring 25, in which case the cam 29 moves inwardly beyond the arm 28 so that the spring 31 can exert its force thereon to move the arm 28 from the position shown in Figure 9 to that shown in Figure 10 so as to raise the forwardly extending hook-shaped portion above the pin 30.

An operating arm 32 is secured to the shaft 4 by any conventional means such as a screw 33 as is well known in the art. The shaft 4 is provided with an eccentric or cam 34 which rotates within a slotted lever 35 pivoted to a pin 36, which lever 35 carries an operating dog 37 pivoted thereto as at 38. A spring 39 tends to pull said dog 37 against a stop pin 40 carried by the lever 35. The dog 37 is provided with a pin 41 which engages a star wheel 42 secured to the shaft 15. The shaft 15 is also provided with a pinion 43 which meshes with the gear 9 of the units figure wheel 8. A spring 44 is secured to a bracket 45 which is in turn secured to the end wall 2 of the casing. The spring 44 engages the star wheel 42 and serves as a means to prevent retrograde movement thereof.

In operation, the figure wheels are actuated as follows:

When the actuating arm 32 is either rotated or oscillated forwardly or rearwardly, the lever 35 is oscillated on its pivot 36 so as to alternately move the dog 37 and pin 41 toward and from the star wheel 42 thereby rotating the star wheel 42, the shaft 15 and pinion 43 step by step and thereby actuating

the units figure wheel 8 so as to successively advance the same from one numeral to the next numeral. The transfer pinion 11 is in engagement with the disk 10 on the units figure wheel 8, which transfer pinion is rotated one step when the single tooth on the disk 10 engages therewith, which rotation of the figure wheel advances the tens figure wheel 8 one unit as is well understood by those skilled in the art. It is well known that such transfer pinions are provided with alternating long and short teeth. A spring 53, Figure 6, carried by the member 14 presses against the two top long teeth so that rotation of the transfer pinions is resisted, but this resistance may be easily overcome when the transfer pinion is positively actuated as described above. In like manner the figure wheels of higher denomination are rotated when the units wheel has made a sufficient number of rotations to actuate the figure wheels of higher denomination. All of the figure wheels are resiliently held in position by means of flat springs 46 provided with an inwardly extending detent 47 which engages between two of the teeth on each of the gears 9. These springs 46 are secured to the casing 1 and the tension thereof will be overcome when the wheels are positively actuated. The spring is, however, of a sufficient tension to move the gears and figure wheels either to the higher or the lower number unless the detent 47 should rest squarely on the top of one of the teeth of the gears 9.

When it is desired to reset the mechanism, the knob 20 is moved inwardly against the tension of the spring 25 so as to move the pin 30 out of the hooked end of the arm 28 of the bracket 26. This inward movement of the knob 20 likewise moves the cam 29 inwardly from beneath the rearwardly extending portion of the arm 28. The spring 31 now raises the forwardly extending portion of the arm 28 so that the pin 30 can be rotated rearwardly as viewed in Figure 1, beneath the bracket 26, while the spring 22 pulls the flange 16 inwardly raising the transfer pinions 11 from the position shown in Figure 7 to that shown in Figure 8, or out of contact with the gears 9 and disks 10, while the springs 53 hold the transfer pinions 11 against rotation, so that when the pinions again mesh with the gears, there will be no clashing of teeth. Unless the springs 53 were provided, it might so happen that one of the teeth of the transfer pinions would fall squarely on top of one of the teeth of the gears 9 and therefore fail to properly mesh therewith. The springs 53 effectually eliminate such a possibility. The spring 22 is permitted to thus remove the pinions 11 because of the fact that as the disk 18 moves inwardly the cutaway cam portion 21 moves beneath the inwardly extending ear 17 so that the full force of the spring 22 is ex-

erted on the U-shaped member 14 which carries the shaft 12 on which is mounted the pinions 11.

The pinions 11 now being disengaged from their respective gears and the bracket 28 being removed from the path of movement of the pin 30, the shaft 4 may be rotated in a clockwise direction as viewed in Figure 7, this rotation of the knob 20 being imparted 10 to the shaft 4 by means of a pin 48 carried by the shaft 4 and lying within a cutaway portion 49 of the knob 20. As the shaft 4 is now rotated, no movement is imparted to the figure wheels 8 until the channel 7 is engaged by the dogs 50, whereupon a further 15 rotation of the shaft 4 will cause the figure wheels 8 to be rotated. Inasmuch as all of the dogs 50 are similarly located on their respective figure wheels, and since the numerals 20 on the figure wheels are similarly located with respect to the dogs 50, it is obvious that a continued rotation of the shaft 4 will cause the same number to appear beneath the sight opening 51 in the casing 1. When the knob 25 20 has nearly completed a single rotation, the cam 29 engages the rearwardly extending arm 28 of the bracket 26 and moves it outwardly into the position shown in Figure 9 while the ear 17 holds the flange 18 very close 30 to the end wall 3. When the knob 20 completes its revolution, the pin 30 strikes against the inner wall 52 of the bracket 26 which stops the rotation of the knob 20. The cutaway cam portion 21 is now beneath the ear 17 35 and the spring 25 pushes the knob 20 into the position shown in Figure 1 while the cam 21 moves the ear 17 outwardly so as to rock the member 14 on the shaft 15 and cause the pinions 11 to engage the Geneva wheels connected with the figure wheels. The numerals 40 on the figure wheels are, of course, positioned thereon so that when the counter has been reset as described above, only zeros would appear in the sight opening 51. Obviously this 45 might be changed if special conditions so required. For instance, in taximeters it is not desired to reset the counters to zero but to that arbitrary figure which may represent the initial fare charged the passenger. In such 50 a condition, obviously the numerals on the outside of the units and tens figure wheels would be accordingly changed.

This invention may be used wherever counters are employed, and I therefore do not 55 limit myself to any particular use thereof. Furthermore, many changes may be made in the specific embodiment as shown by way of illustration in this application, and I therefore desire to claim my invention broadly and 60 reserve to myself the right to substitute equivalents and to make all changes and modifications which may fairly fall within the scope of the appended claims.

I claim:

65 1. In a counter, a shaft, counting wheels

rotatably mounted on said shaft, resetting means for said counting wheels, said resetting means including a bracket provided with a slot, a slideable shaft, a pin thereon, means whereby said bracket is raised so that said pin will pass beneath the bracket, and means whereby said bracket is moved so that said pin will engage one side of said slot to limit the rotation of said slideable shaft when the counters have been reset to zero.

2. In a counter, a rotatable shaft, counting wheels rotatably mounted on said shaft, resetting means for said counting wheels, said resetting means including a pivoted bracket provided with a slot, a slideable shaft, a pin thereon, means whereby said bracket is raised so that said pin will pass beneath the bracket, and means whereby said bracket limits the rotation of said slideable shaft when the counters have been reset to zero.

3. In a counter, a shaft, counting wheels rotatably mounted on said shaft, resetting means for said counting wheels, said resetting means including a bracket provided with a slot, a slideable shaft, means whereby said slideable shaft is connected to said first mentioned shaft so that when the slideable shaft is rotated the first mentioned shaft will likewise be rotated, a pin carried by the slideable shaft, means whereby said bracket is raised so that said pin will pass beneath the bracket, and means whereby said bracket is moved so that said pin will engage said bracket to limit the rotation of said slideable shaft when the counters have been reset to zero.

4. In a counter, a shaft, counting wheels rotatably mounted on said shaft, means connecting said shaft and wheels so that when said shaft is rotated said wheels will be reset, a bracket provided with a slot, a slideable shaft connected to said first mentioned shaft, a pin carried by the slideable shaft, which pin normally rests in said slot, means whereby said bracket is raised so that said pin will pass beneath the bracket when the slideable shaft is actuated, and means whereby said bracket is moved so that said pin will engage the sides of said slot and lock the slideable shaft against rotation in any direction.

5. In a counter, a shaft, counting wheels rotatably mounted on said shaft, resetting means for said counting wheels, said resetting means including a pivoted bracket provided with a slot, a slideable shaft, a pin thereon normally resting within said slot, means whereby when said slideable shaft is moved inwardly said bracket will be raised so that said pin will pass beneath the bracket, and means whereby said bracket is moved so that said pin will engage one side of said slot to limit the rotation of said slideable shaft when the counters have been reset to zero.

In testimony whereof I affix my signature.

ROBERT B. LONG. 130
